US00D986202S

(12) **United States Design Patent** (10) **Patent No.:** **US D986,202 S**
(45) **Date of Patent:** **** May 16, 2023**

(54) **ELECTRONIC DEVICE**

(71) Applicant: **Samsung Electronics Co., Ltd.**, Suwon-si (KR)

(72) Inventors: **Jinwoo Lee**, Suwon-si (KR); **Junwon Lee**, Suwon-si (KR); **Namsu Kim**, Suwon-si (KR); **Kangmoon Kim**, Suwon-si (KR); **Dahyun Lee**, Suwon-si (KR); **Jieun Myung**, Suwon-si (KR); **Junho Jin**, Suwon-si (KR); **Jiyoung Lim**, Suwon-si (KR); **Bosoon Kang**, Suwon-si (KR)

(73) Assignee: **SAMSUNG ELECTRONICS CO., LTD.**, Suwon-si (KR)

(**) Term: **15 Years**

(21) Appl. No.: **29/812,267**

(22) Filed: **Oct. 20, 2021**

(30) **Foreign Application Priority Data**

Apr. 29, 2021 (KR) 30-2021-0020868

(57) **CLAIM**

The ornamental design for an electronic device, as shown and described.

DESCRIPTION

FIG. 1 is a front perspective view of an electronic device showing our new design according to a first embodiment; FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is a front perspective view of an electronic device showing our new design according to a second embodiment;

FIG. 10 is a front view thereof;

FIG. 11 is a rear view thereof;

FIG. 12 is a left side view thereof;

FIG. 13 is a right side view thereof;

FIG. 14 is a top plan view thereof;

FIG. 15 is a bottom plan view thereof; and,

FIG. 16 is a rear perspective view thereof.

The dashed broken lines in the figures depict portions of the electronic device that form no part of the claimed design.

(Continued)

The dot-dash broken lines in the drawings define the boundaries of the claimed design and form no part thereof.
